(57) CLAIM

The ornamental design for a combined badge reel and watch face, as shown and described.

DESCRIPTION

FIG. 1 is a right front perspective view of a combined badge reel and watch face showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The structural features depicted by broken lines have been shown for the purpose of illustrating portions of the combined badge reel and watch face that form no part of the claimed design.
